WILLIAM STELZER, OF CHICAGO, ILLINOIS

FLYING MACHINE

Application filed December 17, 1927. Serial No. 240,798.

The invention relates to flying machines having vertically oscillating carrying planes, which are movably supported, so as to adapt themselves simultaneously to the relative air currents at any direction of motion, thereby producing lift and thrust when descending, and the main objects of the invention are, first, to provide a flying machine with vertically reciprocating transverse carrying planes, means to adapt the angle of wing setting automatically to the direction of motion and a power plant reciprocating the said carrying planes; second, to make the angle of wing setting of the carrying planes automatically adaptable to the oscillations by springs giving the carrying planes the tendency to attain a positive angle of attack and to support the carrying planes pivotally at points located forward of the center of the 15 lifting forces, causing the airfoil to incline when descending, therefore effecting lift and thrust and, third; to transmit the vertical movements of the pistons of the power plant directly to the wing, making any rotating parts unnecessary, thereby producing an inexpensive and reliable engine.

It is well known that present day aeroplanes are sustained in the air by accelerating air in a downward direction, which is effected by a power plant turning a propeller and thus accelerating a comparatively small mass of air against the direction of flight in order to move large blades, known as wings or carrying planes, forward, the latter inducing the lift by accelerating the air about it in a downward direction. The aim is to utilize the energy of the fuel to accelerate as large a mass of air as possible in a downward direction in order to produce lift. It is quite obvious, that by transmitting the energy in series by as many elements as described above, only a fraction of the energy is really reaching its destination and producing lift, the rest is lost in friction and by accelerating air in a horizontal direction. Another loss is caused by the induced drag due to the positive angle of wing setting. The energy consumed to thrust the aeroplane forward is only 50 a fraction of the entire energy spent if it is

considered that the wing drag exceeds the parasite drag.

The aim of my invention is to provide an aeroplane with means to transmit the energy from the power plant directly to the carrying planes and to accelerate the air about them in an oblique downward direction pointing backward, producing lift and thrust in a more economic and efficient way than heretofore attained. Therefore a flying machine 55 embodying my invention will have a greater range and carrying capacity, and a higher commercial value than propeller-driven aeroplanes, whose propeller losses and induced drag have kept aviation from a greater success.

Further objects of the invention will appear in the following detailed description, taken in connection with the accompanying drawings wherein:

Fig. 1 is a top plan view of the flying machine, showing two continuous wings mounted in tandem fashion.

Fig. 2 is a longitudinal section taken through the center of the front part of the 75 flying machine.

Fig. 3 is a transverse vertical section taken through the center of the forward unit looking toward the front of the flying machine.

Fig. 4 is a hypothetical diagrammatic view 80 illustrating the pitch of an ascending airfoil in reference to the longitudinal axis X of the aircraft, said axis X being parallel to the direction of normal flight, and the direction of reciprocation being approximately parallel 85 to the normal vertical axis of the said aircraft.

Fig. 5 is a hypothetical diagrammatic view illustrating the inclination of a descending airfoil.

Describing the invention more in detail and with particular reference to Fig. 1 there is illustrated a flying machine embodying a centrally positioned fuselage 27 with the usual empennage 34 thereon comprising a 95 pair of operable transverse planes 35 and a vertical rudder 36, these elements being operable from within the fuselage at a convenient point.

"Geometrically negative inclination of an 100

airfoil" herein designates a position of such airfoil similar to that illustrated in Fig. 5.

In the two cylinders 1 and 2, which are mounted to the fuselage, reciprocate the pistons 3 and 4 connected to the pistons rods 5 and 6 respectively, the latter pass through centrally positioned airtight guides 19 and reciprocate the rigidly secured U shaped rods 7 and 8, whose top ends are formed into clevises bearing the wings 9 and 10 by the pins 26 seated in the lugs 25 extending from the carrying planes. The U shaped rods 7 and 8 pass through and are held vertical by the guides 28 secured to the fuselage 27.

The cylinderheads are provided with openings bearing the exhaust valves 20, which are kept to their seats by the springs 23 and temporarily opened by the lugs 24 extending from the wings 9 and 10. The combustion chambers 29 are equipped with the electric spark plugs 18, which, together with the electric spring contacts 17 fastened to the bottom of the fuselage 27, form part of the ignition system. The chambers below the pistons 3 and 4 communicate with the carburetor 15 through the short tubes 30 bearing the flap valves 14, which permit the combustible mixture from the carburetor 15 to flow into the cylinders when the pistons move upward and thereby cause a suction. The lower ends of the piston rods 5 and 6 extend into the U shaped tube 21 mounted to the fuselage 27 and to the landing gear housing 31, and are adapted to the ends of the tube 21, which form airtight guides for the said piston rods 5 and 6. The enclosed air thus serves as an elastic lever for the piston rods 5 and 6 and forces the latter to reciprocate alternately. The springs 11 and 12 impress a pitching moment on the wings 9 and 10, to these they are connected by the wires 13 passing through slots in the fuselage skin and to the lugs 16 extending from the rods 5 and 6.

The cockpit 33 has its opening in front of the power plant and is provided with a seat 38 for the pilot and with the means to control the flying machine, the control stick 39 being indicated illustratively in Fig. 2.

The landing gear housing 31 is of streamline shape and extends centrally from the bottom of the fuselage 27. It supports the single landing wheel 37 and the tube 21, at the same time preventing any undesired head-resistance of these elements. The skids 52 extend from the lower longérons of the fuselage and prevent the flying machine from banking when taxiing on the ground. A fuel tank may be mounted into the fuselage at a convenient place with the means to feed the fuel to the carburetor 15, which is shown diagrammatically in Fig. 2, these elements being the usual and forming no part of this application will not be described.

The operation is as follows:

Supposing the flying machine is at rest

on the ground and its engine has to be started, the wings 9 and 10 have to be reciprocated manually to fill the combustion chambers 29 with a combustible gas-mixture and to compress the latter before being ignited by an electric ignition system, whose timing apparatus is replaced by the contacts 17, which close the circuit when touched by the lugs 16. The wiring connections are made in such a way that by closing the rear contact the gas-mixture in the cylinder will be ignited and that the closing of the forward contact will effect the ignition in the cylinder 2.

Referring to Fig. 2, the illustration corresponds to a working stroke in the rear cylinder 2, with the ignited gases expanding, pressing the wing 10 down and the wing 9 up due to the action of the air in the communicating tube 21. In the cylinder 2 the exhaust valve 20, as well as the check valves 22 and 14, is closed and the combustible gas-mixture below the piston 4, which was sucked in previously through the carburetor 15, is being compressed. The descending piston rod 6 compresses the air in the tube 21, forcing the piston rod 5 and the elements attached thereto to ascend, the valves 20 and 22, in the cylinder 1 are kept to their seats and prevent the escape of the gases being compressed in the combustion chamber 29 of the said cylinder 1. In the space below the piston 3 a suction is effected by the said ascending piston 3, allowing air to flow through the carburetor 15, mix with carbureted fuel and pass through the check valve 14 into the said space below the piston 3. At the end of the stroke the lug 24 on the rear wing 10 opens the exhaust valve 20, permitting the spent gases in the cylinder 2 to escape while the compressed gas-mixture below the piston 4 expands and flows through the check valve 22 into the combustion chamber 29, pushing the burnt gases through the exhaust valve 20. At the same time the lug 16 on the rod 8 touches the rear contact spring 17 and thus closes the electric circuit which causes a spark on the forward spark plug 18 projecting into the combustion chamber 29, igniting the combustible gases therein and hereby starting the working stroke of the piston 3. The forward check valve 14 built into the tube 30 communicating with the cylinder 1 has closed itself and the fresh mixed gases are going to be compressed by the descending piston 3, the piston rod 5 attached thereto compresses the air in the tube 21 and forces the piston rod 6 and the elements attached thereto to ascend. The check valve 20 on the cylinder 2 closes again, after the fresh supply of combustible gas-mixture has replaced the exhaust gases and the check valve 14 is opened by the inflowing gas-mixture, the check valve 22 being pressed to its seat by the combustible gases above the piston 4, which are compressed by the latter. As

the lug 24 secured to the under side of the wing 9 opens the exhaust valve 20, the spent gases in the combustion chamber 29 of the forward cylinder escape and are replaced by the fresh supply of gas-mixture under the piston 3 which is flowing through the check valve 22, while the lug 16, secured to the rod 5 touches the contact spring 17, causing the spark which ignites the compressed combustible gas-mixture in the combustion chamber 29 of the rear cylinder 2, thereby starting the next period of operation perfectly identical to the one described.

The wings 9 and 10 are mounted pivotally to the top ends of the rods 7 and 8 respectively and reciprocate alternately. The lateral axis including the axis of the pins 26, about which each wing is rotatable, is located between the leading edge and the center of active lift; this arrangement effects that each airfoil, when projected through the air, will be given by the latter the tendency to reach the zero-lift angle. This attitude is counteracted by the springs 11 and 12, whose function is to impress a pitching moment on the said airfoils. The springs 11 and 12 exert such a tension that holds the airfoils at the most economic angle of attack, when not reciprocating and projected through the air at a mean speed.

During the reciprocation of the airfoils 9 and 10 the lift induced in the descending airfoil increases and the latter inclines in a geometrically negative direction relative to the longitudinal axis of the aircraft and to its path of flight, but the angle of attack relative to the air remains positive because the airfoil is descending. The downward motion of the inclined airfoil, as illustrated in Fig. 5, effects a thrust upward perpendicular to the wing cord, the components being thrust and lift.

The ascending wing, whose position is illustrated diagrammatically in Fig. 5, maintains a positive angle of pitch but as the springs are almost fully contracted they exert very little force and the airfoil is almost at zero-lift angle, which, due to the upward motion of the airfoil is yet very steep in relation to the longitudinal axis X of the aircraft. This arrangement is chosen to prevent the undesired induced drag, which would be very great if the wings were to produce lift while ascending. After the burnt gases have spent their obtainable energy the airfoils increase the amplitude of the period of reciprocation due to the momentum of their mass, thereby further compressing the gas-mixtures which are not ignited yet. At the turning point of the motion the airfoils have reached the normal angle of wing setting and adapt themselves again to the accelerating motion in the opposite direction, with the tendency described above, therefore the flying machine 65 is thrust forward and lifted alternately

by the airfoils 9 and 10. The latter are constructed in such way as to have their mass perfectly balanced, for instance by providing a single twist free spar or truss in each wing slightly ahead of the supporting points, or by reinforcing the airfoil around the entering edge, which is effected on present day carrying planes by wing rib formers or by using plywood as wing covering from the spar to the leading edge.

The combination of the wings 9 and 10, both rotatable about the pins 26, together with the wires 13 and the springs 11 and 12 has such characteristics whereby the flying machine can be partly used for dynamic soaring flight, by utilizing the momentum of turbulent air as occurs during strong winds, when the air not only flows in a longitudinal direction, but also oscillates vertically. An upward air current produces a lift in the wings 9 and 10 but instead of the induced drag resulting in an aeroplane with fixed airfoils having a positive angle of wing setting, a thrust is induced due to the negative inclination of the wings 9 and 10, said inclination being caused by the increased lift. During a down current the springs 11 and 12 contract, as the lift diminishes, thus causing the wings to pitch. The descending air current thereby is prevented from pressing the aircraft down, the latter travelling by its own momentum until the air current has reversed.

While there are herein shown and described the preferred embodiments of the invention with two wings mounted in tandem fashion in combination with a power plant adapted to reciprocate said wings, the latter being located above the center point of gravity to make a lateral balancing mechanism superfluous, it may be nevertheless understood that the invention can be carried out in ways different from that shown without departing from the spirit and scope of the invention. As for instance any number of wings mounted in tandem fashion or one above the other may be used, reciprocated vertically or in an oblique line by a power plant as described in this application or any standard engine, the reciprocating motions of the wings being brought about by a crank shaft.

Two alternately reciprocating wings have been chosen in this application for the embodiment of my invention, because they can give the smoothest working by alternately producing a continuous lift and thrust, and insure a smooth flight due to the balancement of the momentum of the said wings, nevertheless my invention can also be embodied in a flying machine having a single reciprocating airfoil, said airfoil being mounted in the manner described for the tandem flying machine and reciprocated by a standard engine or a single cylinder internal combustion engine conforming with

the system described above, the U shaped tube 21, for instance, being closed on one side so that the enclosed air would serve as a pneumatic spring, to effect an instantaneous ascent of the said single airfoil and to compress the combustible gas-mixture in the cylinder.

For the sake of simplicity of the theory of my invention, I have described the airfoils as stiff continuous carrying planes; nevertheless it may be added, that they can be provided with ailerons operable from within the fuselage, to control the lateral stability of the aircraft, or a stiff lateral truss may be rigidly secured to each of the reciprocating rods 7 and 8, the wing ribs being rotatably mounted about said truss and tended individually by springs to maintain a positive angle of attack.

It is, of course, to be understood that the invention may be constructed in other manners and the parts associated in different relations and therefore, I do not desire to be limited in any manner except as set forth in the appended claims.

Having thus described my invention, I claim:

1. In aircraft, the combination of a fuselage, a reciprocating element, an airfoil pivotally mounted to said reciprocating element, the pivotal axis about which said airfoil is rotatable being located forward of the line of action of the resultant air force, spring means to impress a pitching moment on the said airfoil, and means to reciprocate said reciprocating element and airfoil.

2. In aircraft of the class described, in combination, a fuselage, a plurality of alternatingly reciprocating elements, a transverse airfoil pivotally mounted to each of the said reciprocating elements, the lateral axis containing the pivots about which each respective airfoil is rotatable being located forward of the line of action of the resultant air force, elastic means to impress a pitching moment on said airfoils, and means to reciprocate said reciprocating elements and airfoils.

3. In aircraft of the class described, in combination, a fuselage, reciprocating elements, a plurality of transverse airfoils pivotally mounted to each of the said reciprocating elements, the pivotal lateral axis of each airfoil being located forward of the line of action of the resultant air force acting on said respective airfoil, elastic means to impress a pitching moment on the said airfoils, and means to alternatingly reciprocate said reciprocating elements.

4. In aircraft of the class described, in combination with the construction as claimed in claim 1, a single-cylinder engine mounted rigidly to the fuselage, and means to transmit the reciprocating motions of the piston of said engine directly to the reciprocating elements carrying the airfoil.

5. The construction such as disclosed in claim 2, wherein the airfoils are in tandem.

6. The construction such as disclosed in claim 2, wherein the airfoils are superposed.

7. In combination with the construction such as claimed in claim 2, an internal combustion engine having a plurality of cylinders, means to connect the pistons of said engine directly to the reciprocating elements carrying the airfoils, and means to elastically interlock the reciprocating elements so as to reciprocate alternately.

8. In an aircraft, for the purpose of utilizing air currents for motive power, the combination of a fuselage, a frame therein, a transverse continuous airfoil pivotally mounted to said frame, the axis about which the airfoil is rotatable being forward of the center of effective lift induced in the said airfoil, elastic means being to impress a pitching moment on the said airfoil to such an extent as to attain an angle of attack which is the most economic to produce lift during soaring flight, and to attain a geometrically negative inclination during an upward motion of an air current, which gives the maximum of lift and thrust, and means to reciprocate the said frame and the airfoil attached thereto.

Whereupon I affix my signature.

WILLIAM STELZER.
